United States Patent Office.

AARON WARREN WHITNEY, OF WOODSTOCK, VERMONT.

Letters Patent No. 81,048, dated August 11, 1868.

IMPROVEMENT IN TIN-SMITHS' STAKES.

The Schedule referred to in these Letters Patent and making part of the same.

TO ALL WHOM IT MAY CONCERN:

Be it known that I, AARON WARREN WHITNEY, of Woodstock, in the county of Windsor, and State of Vermont, have invented a new and useful Improvement in Tin-Smiths' Stakes; and I do hereby declare that the following is a full, clear, and exact description thereof, which will enable others skilled in the art to make and use the same, reference being had to the accompanying drawings, forming part of this specification, in which—

Figure 1 is a side view, illustrating my improvement in tin-smiths' stakes.

Figure 2 is a top view of the same.

Figures 3 and 4 are detail views of some of the tools, detached.

Similar letters of reference indicate like parts.

My invention has for its object to simplify and improve the construction of tin-smiths' stakes, so as to make them more convenient and less expensive, only one standard being required for a great variety of stakes.

It consists in the construction of the various parts, as hereinafter more fully described.

A represents a portion of the bench, to which the stakes are attached when in use.

B is an upright or standard, upon the lower end of which is formed a rectangular tenon, which fits into a mortise in the bench A, where it may be detachably secured in place by a wedge-shaped key, passed through a hole or slot in said tenon, beneath the said bench.

Upon the upper end of the upright or standard B is formed a round tenon, upon which fits the socket or head C, which is adjustably secured in place by a set-screw, D, passing through the side of the socket C, with its forward end resting against the side of the said tenon.

If desired, the head or socket C may be formed solid upon the upper end of the upright or standard B, but I prefer the construction first described, as enabling the tool to be adjusted into any desired position.

Upon the opposite sides of the socket or head C are formed arms E, having sockets formed in their ends to receive the tenons formed upon the bases or inner ends of the stakes F, which are removably secured in place by set-screws G, or by other convenient means. This allows the tool to be readily detached when not required for use, and replaced by a tool of another form, so that only one upright or standard will be required for an indefinite number of stakes.

Having thus described my invention, I claim as new, and desire to secure by Letters Patent—

1. The socket or head C, having two or more socket-arms, E, formed upon its sides, in combination with the upright or standard B, whether said socket or head C is formed solidly upon or is detachably and adjustably secured to said upright or standard B, substantially as herein shown and described, and for the purpose set forth.

2. Forming the stakes F without shanks, and with tenons upon their inner ends, to adapt them to the socket-arms E of the socket or head C, substantially as herein shown and described, and for the purpose set forth.

AARON WARREN WHITNEY.
